UNITED STATES PATENT OFFICE.

ERVIN S. BOARDMAN, OF THORP, WISCONSIN.

EGG-STRAP AND FASTENER.

1,304,532.

Specification of Letters Patent. Patented May 27, 1919.

Application filed August 8, 1918. Serial No. 248,931.

To all whom it may concern:

Be it known that I, ERVIN S. BOARDMAN, a citizen of the United States, residing at town of Thorp, in the county of Clark and 5 State of Wisconsin, have invented a new and useful Egg-Strap and Fastener, of which the following is a specification.

The device forming the subject matter of this application is a fastener, adapted to be 10 applied to egg cases and like receptacles, to hold the lid closed thereon, and one object of the invention is to provide novel means for releasably connecting said parts of the structure.

15 A further object of the invention is to improve generally and to enhance the utility of devices of that type to which the present invention appertains.

With the above and other objects in view 20 which will appear as the description proceeds, the invention resides in the combination and arrangement of parts and in the details of construction hereinafter described and claimed, it being understood that 25 changes in the precise embodiment of the invention herein disclosed can be made within the scope of what is claimed, without departing from the spirit of the invention.

In the accompanying drawings:—

30 Figure 1 is a front elevation showing a receptacle whereunto the structure forming the subject matter of application has been applied;

Fig. 2 is an elevation, fragmental in nature, and showing certain parts of Fig. 1 on an enlarged scale;

Fig. 3 is an end elevation of the receptacle, with the device forming the subject matter of this application mounted thereon;

40 Fig. 4 is a sectional detail taken through the receptacle at the rear upper corner; and

Fig. 5 is a section taken on the line 5—5 of Fig. 2.

In carrying out the invention, there is 45 provided a receptacle including a box like body 1 and having a lid 2. The body and the lid are surrounded at both ends of the receptacle, if desired, by duplicate structures, but one of which need be described.

50 Each one of these structures includes a strap, preferably made of metal, and including a base 3 bent to form a front strip 4. The rear end of the base 3 is detachably connected as indicated at 5 with an upright back strip 6. The numeral 7 denotes a top strip 55 extending transversely of the lid 2. The

back strip 6 and the top strip 7 are provided with eyes 8 connected by a loop shaped link 9, a pivotal union between the lid 2 and the body 1 thus being provided. The top strip 60 7 may be connected to the lid 2 by means of securing devices 10, the parts 6, 3, and 4 being united with the body 1 by means of securing devices 11.

The numeral 12 marks a keeper having an 65 eye 14, and there is an eye 14^a at the front end of the top strip 7. A loop shaped link 15 is mounted in the eyes 14 and 14^a, and thus the keeper 12 is pivoted to the top strip 7, the link 15 being curved so as to extend 70 across the forward edge of the lid 2, as shown clearly in Fig. 5. Below the eye 14, the keeper 12 is provided with apertures 16, and at its lower end, the keeper is broadened to form a head 17 defining shoulders 18. 75 There is an opening 19 in the head 17. A loop shaped retainer 20 slides on the keeper 12, between the shoulders 18 on the one hand, and the eye 14 on the other hand. The upper end of the front strip 4 is reduced 80 in width to form a tongue 21. The tongue 21 extends behind the head 17 and outwardly through the opening 19, the upper end of the tongue being overlapped on the forward face of the keeper 12. The upper end of the 85 tongue 21 is provided with a rearwardly extended finger 22, adapted to be engaged in the apertures 16 of the keeper 12. When the retainer 20 is shoved downwardly against the shoulders 18, the retainer receives the 90 upper end of the tongue 21 and houses the same, the finger 22 being retained in one of the apertures 16. By sliding the retainer 20 upwardly, off the upper end of the tongue 21, the finger 22 may be swung backwardly 95 out of the opening 19, and the lid 2 may be swung backwardly with the link 9, the head 17 being carried upwardly off the upper end of the keeper 12.

The device forming the subject matter of 100 this application includes, briefly stated, a first member 7; a keeper 12 pivoted at 15 to the first member and having an enlarged head 17 defining a shoulder 18, the head being provided with an opening 19, and the 105 keeper 12 being provided with an aperture 16; a second member 21 extended behind the head 17 and outwardly through the opening 19, the second member having a finger 22 received in the aperture 16; and a loop 110 shaped retainer 20 slidable on the keeper 12 and receiving the end of the second member

21 to hold the finger 22 in the aperture 16, the shoulder 18 forming a stop for the retainer.

Having thus described the invention, what 5 is claimed is:—

An egg strap and fastener comprising a first member; a keeper pivoted thereto and having an enlarged head defining a shoulder, the head being provided with an opening, and the keeper being provided with an aperture; a second member extending behind the head and outwardly through the opening, the second member having a finger

received in the aperture; and a loop shaped retainer slideable on the keeper and receiving 15 the end of the second member to hold the finger in the aperture, the shoulder forming a stop for the retainer.

In testimony that I claim the foregoing as my own, I have hereto affixed my signature 20 in the presence of two witnesses.

ERVIN S. BOARDMAN.
